UNITED STATES PATENT OFFICE.

THOMAS A. SMITH, OF AZUSA, CALIFORNIA.

SWITCH AND MEANS FOR OPERATING SAME.

SPECIFICATION forming part of Letters Patent No. 627,883, dated June 27, 1899.

Application filed March 13, 1899. Serial No. 708,925. (No model.)

To all whom it may concern:

Be it known that I, THOMAS A. SMITH, a citizen of the United States, residing at Azusa, in the county of Los Angeles and State of California, have invented certain new and useful Improvements in Switches and Means for Operating the Same, of which the following is a specification.

My invention relates to improvements in switches and an operating mechanism therefor, and has special reference to a switch to be used upon tramways and steam-railroads, the cars and locomotives upon said tramways and railroads having a device attached thereto to operate the switch automatically.

The main object of my invention is the provision of a switch which has a simple mechanism which is operated to close the frog to form a switch and devices to cause the mechanism to assume its normal or open position.

Another object of my invention is the provision of a switch and mechanism to operate the same which is the embodiment of simplicity, durability, and inexpensiveness, as well as a very thorough, efficient, and practical device.

To attain the desired objects, the invention consists of a switch and an operating mechanism therefor embodying novel features of construction and combination of parts substantially as disclosed herein.

Figure 1 is a perspective view of a portion of a tramway-track, showing my improved switch and a car carrying the operating mechanism. Fig. 2 is a top plan view of a portion of a track, showing my improved switch. Fig. 3 is a bottom plan view of the switch and its mechanism, and Fig. 4 is a side elevation of the switch-operator as carried by the car-platform.

In the drawings, A designates a base having mounted thereon the track-rails B, and in the center of this base between the tracks is the arc-shaped opening or slot C, upon both sides of which and secured to the top of the base are the switch-operator guiding-strips D and E. Near one of the rails is the switch-rail F, having a slot G, in which is pivotally secured the frog or switch H, which has formed integral therewith and depending therefrom through the rectangular opening J in the base the lug or abutment K, against which con-

tacts the free end of the flat spring L, having its rigid end secured in the block L', upon the under side of the base, this spring being 55 adapted to hold the switch or frog open. To throw the switch into use or close the frog, I employ the long arm or lever M, which is pivoted in its center, and thereby secured to the under side of the base by means of the pin or 60 pivot M', said lever having a pin or projection N, carrying the revoluble collar or band O upon one end, adapted to pass upward through the arc-shaped slot C, and a recessed cut-away portion P in its other end, a pin or 65 projection Q being near this extreme end and just projecting so that its top is flush with the upper surface of the lever.

Pivottally secured, by means of the pin R, to the under side of the base near the recessed 70 end of the lever is the frog-operating dog or hammer S, whose head S' is adapted to strike against the lug of the switch-frog, when the recessed end of the lever is moved, as the pin Q slides in the long slot T, formed in the dog, 75 and causes the said dog to move into and out of contact with the projection of the frog as the lever is moved by the runner U, swingingly hung upon the car-platform by means of the journals or bearing V and the arms V', 80 said runner being thrown into and out of use by means of the long curved lever W, carrying the spring-controlled dog, rod, and hand-lever-catching device X, the dog of which is adapted to engage the notched plate Y. This 85 lever W is journaled in the notched plate Y and the bracket Z, both of which are secured upon the upper side of the platform of a car. As this runner is lowered and enters the space between the guide-strips D and E and has 90 passed through same the spring Z' returns the lever M to its normal position, thus causing the switch to be released and opened.

From this description, taken in connection with the drawings, the operation of my device 95 is readily understood; but, briefly stated, it is as follows: As the car nears the portion of the track upon which my switch is placed the lever carrying the runner is pulled backward to lower the runner, which enters the 100 space between the guide-strips and contacts the projection upon the end of the lever M, upon which is the friction-reducing collar. The lever is then pushed forward, causing the

dog or hammer to contact the lug of the frog, which is closed to form the switch, and as the runner disengages with the projection of the lever the springs L and Z' return the frog and lever M, respectively, thus opening the switch. The lever carrying the runner on the car is then pushed forward, which raises the runner out of use.

It is clearly evident that I provide a simple, durable, and cheap switch and an operating mechanism therefor which is thoroughly efficient and practical and very useful.

I claim—

1. In combination with a switch, consisting of a base-plate provided with a curved slot and a rectangular opening therethrough, a lever pivoted to the under side of said plate, a projection upon one end of said lever adapted to fit and slide in said slot of the plate, a pin carried by the other end of said lever, a striker or hammer pivoted to the under side of the plate and provided with a long slot, in which said pin of the lever is adapted to fit and slide, a frog pivoted to a rail upon the upper side of the plate and having a depending lug entering said rectangular opening of the plate, and springs upon the under side of the plate adapted to hold the lever and frog while not in use, of a switch-operating device

carried by a car or locomotive adapted to contact and close the switch.

2. In combination with a switch, consisting of a base-plate provided with a curved slot and a rectangular opening therethrough, a lever pivoted to the under side of said plate, a projection upon one end of said lever adapted to fit and slide in said slot of the plate, a pin carried by the other end of the lever, a striker or hammer pivoted to the under side of said plate and provided with a long slot in which said pin of the lever fits and slides, a frog pivoted to a rail upon the upper side of the plate and having a depending lug entering said rectangular opening of the plate, and springs upon the under side of the plate adapted to hold the lever and frog while not in use, of a switch-operating device adapted to be carried by a car or locomotive, consisting of a long runner pivotally or swingingly connected to the under side of said car or locomotive, and a handle connected with said runner and adapted to hold it in and out of use.

In testimony whereof I affix my signature in presence of two witnesses.

THOMAS A. SMITH.
